(57) **CLAIM**

The ornamental design for the lamp housing, as shown and
described.

DESCRIPTION

FIG. 1 is a front side elevational view of the lamp housing
in accordance with my design, the rear side being substan-
tially identical thereto;

FIG. 2 is a left side elevational view of the lamp housing in
accordance with my design, the right side being substan-
tially identical thereto; and,

FIG. 3 is a top plan view of the lamp housing in accordance
with my design; and,

FIG. 4 is a bottom plan view of the lamp housing in
accordance with my design.

The curving repeated lines on the surface of the panes of the
lamp housing are intended to indicate a uniform patterned
finish on the surface of the glass and are partially shown for
convenience.
